(57) **CLAIM**

The ornamental design for a cat litter box, as shown and described.

DESCRIPTION

FIG. 1 is a front perspective view of a cat litter box, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged detail view of area 9 in FIG. 1; and, FIG. 10 is an enlarged detail view of area 10 in FIG. 1.

The long dash-short dash-dot broken lines encircling the enlarged views in FIGS. 1, 9 and 10 show the boundaries of the enlargements shown in FIGS. 9 and 10 and form no part of the claimed design. The remaining broken lines in the drawings illustrate the portions of the cat litter box, which form no part of the claimed design.
